UNITED STATES PATENT OFFICE.

FRANK W. HARRIS, OF FAYETTEVILLE, NEW YORK.

GRATE.

1,058,235.

Specification of Letters Patent.

Patented Apr. 8, 1913.

Application filed September 12, 1912. Serial No. 719,969.

To all whom it may concern:

Be it known that I, FRANK W. HARRIS, of Fayetteville, in the county of Onondaga, in the State of New York, have invented 5 new and useful Improvements in Grates, of which the following, taken in connection with the accompanying drawings, is a full, clear, and exact description.

This invention relates to certain improvements in grates for boilers, furnaces and stoves and other heating apparatus for burning solid fuel and refers more particularly to the construction and relative arrangement of the grate-bars.

15 The main object is to enable the grate-bars to be shaken for discharge of the fine ashes therefrom without liability of dumping the live coals and at the same time permitting the entire body of fuel and ashes to 20 be gradually discharged or dumped when desired without displacing the grate-bars from their normal operative position in the manner hereinafter more fully described.

Other objects and uses will be brought out 25 in the following description.

In the drawings—Figure 1 is a top plan of a system of grate-bars and a supporting-frame therefor together with means for simultaneously rotating or rocking all of the 30 grate-bars. Fig. 2 is an enlarged plan of one of the grate-bars. Fig. 3 is a still further enlarged end view of one of said bars. Fig. 4 is an enlarged transverse sectional view of the same bar taken on line 4—4, 35 Fig. 2.

As illustrated, this grate comprises a main supporting-frame —1— and a plurality of, in this instance four, cylindrical grate-bars —2— arranged side by side in parallelism 40 with their meeting faces in close proximity but slightly separated to avoid contact and permit the finer ashes to sift through the intervening spaces, the ends of the bars being reduced in diameter, and are journaled in 45 suitable bearings in the adjacent ends or sides of the main supporting-frame —1—.

The bearings at one end of the frame are preferably open at the top to permit the bars to be readily inserted and removed 50 when desired and the adjacent ends of the grate-bars are provided with intermeshing gears —3— preferably of the same size for simultaneously rotating the bars and causing their meeting faces to travel in the same 55 direction or in rolling relation to each other.

One end as —2'— of one of the grate-bars

protrudes slightly beyond the corresponding ends of the other bars as shown in Fig. 1 and is angular in cross section for the reception of a suitable implement whereby the 60 grate-bars may be rocked or rotated to remove the ashes or dump the fuel in the manner hereinafter more fully described.

Each grate-bar is provided with one or more, in this instance two, diametrically 65 opposite spiral grooves —4— running lengthwise in the periphery thereof from end to end and preferably curved in cross section and is also provided with a series of annular grooves —5— of uniform width 70 intersecting the spiral grooves —4— and forming a series of intervening annular ribs —6— which are also of uniform width substantially equal to the width of the intervening grooves —5—. These ribs and 75 grooves, therefore, alternate with each other throughout the length of the bar and are provided in their peripheries with diametrically opposite spiral recesses forming portions of the spiral grooves —4—. Each 80 spiral groove preferably extends once around the periphery of the bar and, therefore, terminates at its ends at one and the same side of said bar. These bars are assembled in the frame in such manner that 85 their annular grooves are in transverse alinement with each other and, therefore, the annular ribs of adjacent bars are also in transverse alinement, the spiral grooves in adjacent bars being arranged in reverse 90 order or inclination so that the spiral recesses in the annular ribs of adjacent bars will progressively register with each other from end to end or from any intermediate point toward either end as the bars are 95 rotated.

In assembling the bars in the manner just described, it is evident that a series of pockets will be progressively formed by the recesses in adjacent faces of coacting ribs 100 into which pockets the ashes or fuel or both gravitate and may be discharged therefrom at will by the rotation of the bars, such discharge, however, being gradual for the reason that only one pocket is formed 105 at a time by the registering recesses of coacting ribs. In this manner, I am able to shake the grate to free it from ashes without liability of dumping the fuel, while on the other hand, if it is desired to dump the 110 fuel with the ashes, it is simply necessary to rotate the grate-bars continuously in

one or the opposite direction, in which case the downwardly moving upper sides of the recesses at the meeting faces of adjacent bars will operate to force the ashes and fuel downwardly but progressively from one end toward the opposite end of the grate-bars.

5 What I claim is:

1. In a grate, a grate bar having annular ribs spaced apart and provided with registering recesses in their peripheries, arranged to form spiral grooves lengthwise of the bar.
- 10 2. In a grate, a grate bar having annular ribs spaced uniform distances apart and provided with registering recesses in their peripheries arranged to form spiral grooves lengthwise of the bar.
- 15 3. In a grate, a grate bar having annular ribs of uniform width spaced equi-distant apart substantially equal to the width of the ribs and provided with registering recesses in their peripheries arranged to form spiral grooves.
- 20 4. In a grate, a cylindrical grate bar having lengthwise spiral grooves in its periphery and annular grooves intersecting the spiral grooves.
- 25 5. A grate composed of cylindrical grate bars arranged side by side and provided

with lengthwise spiral grooves and annular grooves intersecting the spiral grooves.

6. A grate composed of cylindrical grate bars arranged side by side and provided with lengthwise spiral grooves and annular 35 grooves intersecting the spiral grooves, the annular grooves of adjacent bars being alined transversely.

7. A grate composed of cylindrical grate bars arranged side by side and provided 40 with lengthwise spiral grooves of the same pitch and annular grooves intersecting the spiral grooves, the spiral grooves of adjacent bars being disposed to progressively register with each other at all points in 45 their lengths as the bars are rotated, and means for simultaneously rotating the bars at the same speed.

8. In a grate, a grate bar provided with annular ribs positioned at regular intervals 50 thereon and a recess in the periphery of each rib registering to form a spiral channel lengthwise of the bar, broken by the spaces between the ribs.

In witness whereof I have hereunto set 55 my hand this 6th day of September 1912.

FRANK W. HARRIS.
